UNITED STATES PATENT OFFICE.

JOHN E. PERRY, OF SHARON, PENNSYLVANIA.

INGOT MOLD AND STOOL THEREFOR.

Application filed January 21, 1926. Serial No. 82,635.

This invention relates to metallurgy and especially to mold structures more particularly adapted for the production of steel ingots and the like.

5 This invention comprises novel features in the mold, novel features in the stool, and also the combined novelty of the stool and the mold in their assembled relation ready to receive molten steel or the like.

10 The objects of the invention will be apparent from an understanding of the structures, preferred forms of which will be more specifically described in the specification following by reference to the accompanying drawings forming a part of this application.

15 Realizing that the present invention may be embodied in structures other than those disclosed herein, it is to be understood that the said disclosure is illustrative and not to be considered in the limiting sense.

20 Heretofore in the art it has been customary to use ingot molds comprising a tubular structure usually tapered, and with the said molds adapted to be set upon flat casting bottoms referred to as stools. Difficulties are numerous in connection with this type of construction in that the stool tends to burn out from beneath the mold and often forms cavities that produce fins, bumps, or 25 protuberances on the ingot which overlap the end of the mold and interfere with subsequent operations such as stripping, rolling, etc., and produce steel of inferior quality in the ingot itself.

30 These difficulties are magnified where molds of the big-end-up type are used, in that any tendency to form a fin or interlocking portion between the ingot and the mold structure at the bottom of the mold produces defects in the steel ingot cast in such mold. For example, where a big-end-up mold is used and a fin or bump occurs at the bottom of the set-up, when this portion of the steel freezes or solidifies it firmly anchors the bottom of the ingot to the bottom 35 of the mold so that when the mold is filled with steel and it freezes the taper of the big-end-up mold tends to prevent a downward movement of the upper part of the ingot and the frozen interlock lower part tends to prevent upward movement of the lower part 40 of the ingot so that during the freezing operation the ingot literally pulls itself apart, thus forming cracks, and bad steel structure 45 in the ingot is thereby the result.

The present invention overcomes many difficulties in the known prior art by providing a mold and a stool so constructed as to form a tight metal to metal joint adjacent the bottom of the mold, consequently obviating any formation of fins or other protuberances tending to interlock the ingot and the mold. The invention is useful with either big-end-down or big-end-up type of molds. It comprises the further thought 50 of providing a construction whereby the mold and stool are formed with mutual guides in such manner that when the crane is operated to set the mold on the stool, the mold automatically assumes a definite fixed 55 relation to the stool. This enables the stool to be provided with a relatively small joint surface which may be accurately formed in any practical manner. Preferably, this surface on the stool is obtained by casting the 60 stool against a chill plate, which has the further advantage of hardening the upper surface of the stool and thereby increasing the 65 ability of the stool to withstand cutting effects from the hot steel poured into the set-up. The accurate positioning of the mold upon the stool is particularly desirable 70 where the cross-section of the mold is rectangular, or of a geometric shape other than circular, in that it permits a definite relation 75 to be automatically maintained between the matrix surface on the stool and the matrix of the mold.

Having generally described the invention, the specific preferred embodiments 80 disclosed in the drawings are designated by like characters throughout the several figures thereof. It is to be understood that the mold and the stool may be cast from cast iron, or other materials well known in the 85 art.

Fig. 1 illustrates a portion of a mold and a stool in cross-section showing wedge-like guides on the stool and cooperating lugs on the mold.

Fig. 2 is a plan view of the construction 90 illustrated in Fig. 1 and showing the mold in cross-section.

Fig. 3 is a cross-sectional view of the bottom of a mold and of a stool whereby the mold is guided by the lower portions thereof without the use of lugs on the mold.

Fig. 4 is a detailed view of the bottom of a mold and a stool, in cross-section, provided 95 with four interlocking guiding devices.

Fig. 5 is a plan view of the stool illustrated in Fig. 4 and showing the bottom of the mold in cross-section.

Referring now to the drawings and more especially to Figures 1 and 2 thereof, the section of the mold 1 is that of a mold having substantially a rectangular shaped matrix in cross-section and with the bottom 4 of the mold comprising substantially a plane surface. This surface may be obtained in several ways such as machining, chipping or grinding but preferably is obtained by careful casting of the mold. In the form illustrated in Figures 1 and 2 projections 5 are cast adjacent the bottom of the mold and preferably integral therewith. The bottom corners or edges of these projections are definitely positioned from the axis of the mold in order to comprise guiding members.

The stool adapted to cooperate with this mold shown in Fig. 1 comprises a relatively flat large casting having guiding ears 6 which, in the preferred form, extend upwardly and outwardly to provide guide surfaces 7 adapted to cooperate with the ears 6 to accurately center the bottom of the mold relative to the stool. In the form illustrated in Figs. 1 and 2 a small annular shelf or shoulder 8 is provided adjacent the joint of the mold with the stool and the central part of the stool is cupped. This cup 2 in the stool forms an extension on the end of the ingot cast therein whereby undesirable dendritic crystallization is obviated, and the annular shelf or shoulder 8 between the mouth of the cup 2 and the lower inner corner of the mold prevents hot molten steel from burning out the sharp corner of the mold which sets tightly upon the stool to form a metal to metal joint and thereby obviates any formation of fins between the stool and the mold without the necessity of using any luting material. In this type of mold the centering of the mold on the stool so that the axis of the matrix of the mold is substantially coincident with the center of the cup 2, is particularly important because in order to obtain the best results it is desirable that the shoulder 8 shall be of uniform width entirely around the axis of the bottom of the matrix of the mold, and furthermore in the continued use of the mold there is a tendency of the shoulder becoming worn and cut away to a certain extent and unless succeeding mold set-ups are accurately set in the same position as the preceding set-ups, there may be danger of fins forming under the edge of the mold. The outer portion 9 of the stool is at a lower level than the seat for the mold in order to provide an annular raised platform 10 upon which the mold sets. This platform, as well as other parts of the stool, preferably is formed by casting the upper surface of the

stool against an accurately formed chill plate. This produces a chilled surface having a close grain and with the major portion of the free carbon in spheroidal form over the matrix portion of the stool and also over the mold seat on the stool. These chilled surfaces are particularly well adapted to withstand wear and thus prolong the life of the set-up.

The constructions disclosed in Figs. 1 and 2, therefore, provide a mold set-up in which an accurate metal to metal tight joint is automatically formed between the stool and the mold and is maintained throughout the life of the mold for the reason that the guiding projections on the mold and the guiding ears on the stool always center the mold properly over the stool for each mold set-up. This prevents the setting of the mold over any part of the stool which has been subjected to hot metal and which may have been eaten away or eroded by contact with the hot metal. This construction also obviates the lifting of the mold from a proper seat upon the stool in view to any accidental setting of the mold upon scuff, or other deleterious material which may tend to build up some part of the stool which has been in contact with hot metal. If the mold is set upon such a portion of a stool it opens the joint between the mold and stool at other points, where the scuff may not be so thick, and the obvious result is an undesirable fin on the end of the ingot.

Figure 3 illustrates a construction whereby the mold side walls as at 11 are the guides which cooperate with the guiding ears on the stool. In the construction disclosed in Fig. 3 the central portion of the stool is indicated as being substantially flat but it will be observed that the relation of the bottom of the mold to the stool, maintained because of the guiding ears 6, is such that the mold always sets upon the same annular raised portion of the platform 10, at each set-up, and therefore any irregularities that may form in that portion of the stool comprising a part of the matrix of the mold, is always positioned within the mold and never under that part on which the mold sets.

Figs. 4 and 5 illustrate a construction in which the bottom of the mold is provided with four diametrically oppositely disposed guide lugs 26 and the stool is provided with four pairs of guiding ears 27, 28, 29 and 30 having inclined surfaces 31 and 32 thereon so constructed as to guide the mold into position both laterally and rotatably as the mold is centered over the stool.

In the constructions herein disclosed both a plane surface stool and a stool having a recess therein are illustrated, and the matter of rotative setting of the mold upon the stool is, perhaps, more important in connection

- with the recessed stool than it is with the plane stool, with the exception that in all cases it is a prime object of the present invention to provide a plurality of stools and molds which are adapted to be interchanged during working conditions in such manner that stools and molds of the same size will always cooperate together with assurance that the mold will occupy exactly 5 the same position on the stool as that occupied by the preceding mold. Under these conditions the seating area on the stool is always a constant predetermined area and the matrix portion of the stool is always the 10 same for each succeeding set-up.

Having thus described my invention, what I claim is:

1. The combination of an open-bottom ingot mold for casting steel ingots and a stool 20 for said mold, said mold having a substantially plane bottom, guiding lugs upon said mold adjacent the bottom thereof, said stool having a substantially plane seat for said mold whereby a close metal to metal joint 25 is formed between said mold and said stool, and guiding means cooperating with the lugs on said mold to definitely position said mold on the seat on said stool.

2. The combination of an ingot mold for 30 steel ingots, a stool provided with a mold seat upon which said mold is adapted to set, and inclined guiding means spaced apart from the mold seat to automatically and definitely position said mold on said stool 35 during the lowering of said mold in position upon said stool, there being spaces intervening the mold and the stool between the base of the guiding means and the mold seat.

3. In combination, a vertical mold for 40 steel ingots having substantially a plane bottom and a stool upon which said mold is adapted to set to form a metal to metal joint and with a portion of the stool forming the lower matrix wall for the mold, said 45 stool being formed of cast iron and having a chilled surface adapted to comprise said matrix wall.

4. In combination, a vertical open-bottom

mold for steel ingots having substantially a plane bottom and a stool upon which said 50 mold is adapted to set to form a metal to metal joint and with a portion of the stool forming the lower matrix wall for the mold, said 55 stool being formed of cast iron and having a chilled surface adapted to comprise said matrix wall, and means to definitely position said mold upon said stool.

5. The combination of a vertical ingot mold for steel and having a plane open-bottom, a cast iron stool provided with a raised 60 seat adapted to cooperate with the bottom of said mold to form a close metal to metal joint, said seat upon said stool comprising a chilled cast iron surface.

6. As an article of manufacture, the cast 65 iron ingot mold for manufacturing steel ingots comprising a substantially open tubular body with the bottom substantially plane, and guiding lugs upon said mold adjacent the bottom thereof. 70

7. As an article of manufacture, a stool for ingot molds and having a work surface thereon of close grained metal with the major portion of the free carbon thereof in substantially spheroidal form adjacent said 75 work surface.

8. As an article of manufacture, a stool for ingot molds comprising a cast iron body portion having a substantially plane raised platform comprising a seat for suitable 80 open-ended ingot molds and mold guiding means adjacent said seat.

9. The combination of an open bottom ingot mold for steel ingots, a stool provided with a mold seat adapted to form a tight 85 metal to metal joint with said mold, said stool being provided with a cup of less diameter than the matrix of the mold at the bottom of the mold to comprise a shoulder between the bottom of the mold and the 90 mouth of the cup, and guiding means to cause said mold to rest upon the same portion of the mold seat for each set-up of the mold and the stool.

JOHN E. PERRY.
